(57) **CLAIM**

The ornamental design for a glove, as shown and described.

DESCRIPTION

FIG. 1 is a front perspective view of a first embodiment of a glove showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a rear left perspective view thereof;

FIG. 7 is a front perspective view of a second embodiment of a glove showing our design;

FIG. 8 is a front elevation view thereof;

FIG. 9 is a rear elevation view thereof;

FIG. 10 is a left side elevation view thereof;

FIG. 11 is a right side elevation view thereof; and,

FIG. 12 is a rear left perspective view thereof.

The even length dashed broken lines in the drawings illustrate portions of the glove that form no part of the claimed design.

The uneven length dot-dash broken lines in the drawings represent an unclaimed boundary line and form no part of the claimed design.

Views of the glove not shown in the figures form no part of the claimed design.

1 Claim, 10 Drawing Sheets
